[57] CLAIM

The ornamental design for a golf putting head, as shown and described.

DESCRIPTION

FIG. 1 is a perspective view of the golf putting head
showing my new design;
FIG. 2 is a top plan view;
FIG. 3 is a left-side elevational view, the right-side
being a mirror image thereof;
FIG. 4 is a front elevational view;
FIG. 5 is a rear elevational view; and
FIG. 6 is a bottom plan view.
